UNITED STATES PATENT OFFICE.

JOHN HARRIS, OF BRANTFORD, ONTARIO, CANADA.

REAPING-MACHINE.

SPECIFICATION forming part of Letters Patent No. 248,929, dated November 1, 1881.

Application filed December 10, 1880. (No model.)

To all whom it may concern:

Be it known that I, JOHN HARRIS, of Brantford, in the county of Brant, in the Province of Ontario, Canada, manufacturer of agricultural implements, have invented certain new and useful Improvements in Harvester-Rakes, of which the following is a specification.

My invention relates to improvements in harvester-rakes; and it consists in the peculiar arrangement and construction of the parts, ¹⁰ as hereinafter more fully set forth.

Figure 1 is a plan of a portion of the machine to which my improvements relate. Fig. 2 is a sectional detail of the rake-support, with ¹⁵ a portion of its attachments. Fig. 3 is a perspective view of the rake-wheel and arms. Fig. 4 is a detail showing connection of trip to its operating-crank, also the adjustable throat; and Fig. 5 is a detail showing another ²⁰ view of these parts. Fig. 6 is a bottom view of the slotted arch and its slotted brace.

As my invention relates to improvements on a machine the construction of which is well understood, it will not be necessary for me to ²⁵ enter into a detailed description of its general construction, or to specify the material or dimensions of its various parts. To facilitate the description I shall describe the construction of the parts to which my improvements ³⁰ relate.

In Fig. 2 my improved driving-gear is clearly exhibited. In this figure it will be seen that the shaft A passes through bearings in the rake-support B. These bearings *a*, as shown, ³⁵ are situated on each side of the center of the rake-support, and constitute a solid support for the shaft A.

The upper face of the rake-support B is provided with a central hub, *b*, which forms a journal-bearing for the hub *c* of the rake-wheel D, ⁴⁰ which is adapted to revolve thereon. The rake-wheel D is provided with a circumferential guard or shield *d*, to prevent the ingress of straw or foreign matter, and is provided with a circular row of teeth near its circumference. The rake-support B is provided at its lower ⁴⁵ end, on its grain side, with a curved guard, P, partially inclosing the pinion C, the guards P and *d* serving to protect the pinion from dirt and injury. The pinion C engages with the rake-wheel D on the grain side of the rake-wheel. ⁵⁰

The sprocket-wheel E is keyed or otherwise fastened to the shaft A at the end opposite to the pinion C. This sprocket-wheel is connected by a suitable chain, F, to the main driving-axle G of the machine, whereby the rakes are operated. By this construction and arrangement of the driving mechanism for the rake-wheel with a single shaft, A, passing under ⁵⁵ the rake-wheel and carrying at one end, on the grain side of the rake-wheel, a pinion gearing with it, and carrying on its opposite end gearing connected with the driving-axle by means of which the shaft is driven, the mechanism ⁶⁰ for operating the rake-wheel is simplified over the ordinary construction by using fewer gear-wheels and shafts, and the construction is rendered more compact and cheaper.

A suitable spring belt-tightener, H, situated ⁷⁰ as shown, keeps the chain F always taut. The sprocket-wheel E is so connected to the shaft A that it may easily be removed when desired, and it will be quite evident that by simply changing this wheel for a larger or a smaller ⁷⁵ one the speed of the rake-arms will be increased or diminished without affecting the speed of the cutters, which are driven from the same axle, G.

J (see Fig. 5) represents a casting having an ⁸⁰ inclined cam-plate, R', terminating at its upper end in a horizontal track, R'', and an extension, I, the outer end of which underlaps and fits in a recess in the under face of the track L of the rake-cam, as shown in dotted ⁸⁵ lines in Fig. 5.

h represents a slot in the casting J, and K a bolt having a nut and washer, the bolt being secured to the rake-cam and passing through the slot *h*, by which construction the ⁹⁰ casting J is rendered adjustable to vary the length of the track. As I claim nothing particular in the rake-arms, it is not necessary to describe how they work upon this track, as they operate the same as in the ordinary machine of this class. By having an adjustable casting having an inclined cam-plate I am enabled to lengthen or shorten the track and to set the rakes so that they will travel farther on the platform when heavy grain is being delivered, or to turn up sooner when a lighter ⁹⁵ class of grain is being cut.

In Fig. 4 the gate M is shown open, being held in that position by the tripping-block N.

This tripping-block, as will be seen in Fig. 5, is connected to the crank-lever O by the rod P, and on reference to Fig. 1 it will be noticed that this crank-lever O is likewise attached by 5 rods and lever (marked Q Q') to a foot - lever within reach of the driver. This crank-lever O is provided with an arm, O', which overlaps the face of the rake-wheel D. A pin, R, in the rake-wheel D, is so situated that when passing 10 the arm O' it will come in contact with it, and as this arm is connected through the crank-lever O to the tripping-block N, as described, the latter will be tripped by the action of this pin exactly the same as if the crank - lever O 15 were operated by the driver.

By the insertion of one pin, R, in the rake-wheel, the trip will be set automatically for one rake in four. By placing similar pins on the rake - wheel at the proper points as many 20 more of the rake-heads as may be desired can be thus automatically operated without disturbing the mechanism, which places the tripping apparatus under the control of the driver.

Any one who has studied the operation of 25 reaping-machines is aware of the fact that in reeling short grain it is an advantage to have the rake-support farther back on the machine than when longer grain is being cut. With the view of providing an easy means of accomplishing this end I attach the rake-support B to an arch or supporting-bracket, S, by a bolt, T, which can easily be got at, and as it passes 30 through a longitudinal slot in the arch S, made in the direction of the line of motion of the machine, by loosening the nut on the bolt, the rake-support B may be moved backward or forward as circumstances require. With the view of facilitating this operation, I provide a 35 wrought-iron arch, S, securely bolted to the machine and braced to the frame by the rod U, pivoted at its lower end in a bracket, and provided at its upper end with a slot registering with the slot in the arch S, the bolt T passing through both slots. Heretofore a pinion 40 on a shaft driven by the driving-wheel through intermediate gearing has been arranged on the grain side of the wheel with other gears or pulleys between said pinion and the grain, and a pinion, also driven by a shaft from the main 45 driving-wheel, has been arranged to drive a bevel-gear carrying a pinion that meshes with the rake-wheel, but in neither of these does the shaft that carries the pinion pass across 50 and directly underneath the rake-wheel. These 55 arrangements are not as simple or compact as mine, and they are therefore more likely to get out of order. In my construction the rake-wheel is driven by a pinion on the grain side of the rake-wheel and, operating directly on it 60 and the shaft carrying the pinion, passes directly underneath the rake-wheel.

In that class of machines in which the pinion is on the side farthest from the grain there is the further disadvantage that when the machine is in operation the rake which is clearing 65 the platform is in position to exert the

greatest leverage to cant or tilt the crown-wheel, while its fellow is nearly vertical, and therefore does not counterbalance it, the result of which is to change the pitch-line outward, or a tendency to unmesh the wheels, whereas, by my construction—that is, in extending the shaft across and under the crown-wheel, this greatest leverage tends to keep the wheels in mesh by reason of the driving-pinion being 70 transferred to the side of the crown - wheel which is forced toward the pinion by the weight of the rake-arm. In addition to this advantage, the pinion being on the grain side, being usually smaller than the gear-wheel by which 75 it is driven, can be more readily covered up, and hence is more readily kept free from the straw, &c., which is apt to get caught in the larger wheels when on the grain side.

What I claim as my invention is— 85

1. In combination with the crown-wheel D, provided with a circumferential guard, d, the cross-shaft A, journaled beneath it, said shaft having the rake-driving pinion C on the end of the same on the grain side of the rake-wheel 90 and engaging with the crown-wheel on the under side, substantially as described.

2. The combination, with the geared rake-wheel D, having a circumferential guard, d, of the rake-support B, having the guard P, 95 and the pinion C, inclosed by said guards, substantially as described.

3. The rake-support, B, provided with the journal-bearings a, hub b, and guard P, in combination with the rake-wheel D, provided with 100 a circular row of teeth, circumferential guard d, and hub c, shaft A, carrying the pinion C on the grain side of the rake-wheel, and the sprocket-wheel E on its opposite end, substantially as described. 105

4. The combination, with a rake cam-plate, of the adjustable slotted casting J, provided with the extension I, underlapping the track, inclined cam-plate R', terminating at its upper end in the horizontal track R'', bolt K, and track L, the whole arranged, constructed, and operating as set forth. 110

5. The arch S, securely bolted to the frame of the machine and provided with a slot near its upper end made in the direction of the line of motion of the machine, in combination with the adjustable rake-support B and bolt T, substantially as described, and for the purpose set forth. 115

6. The arch S, provided with a slot at or 120 near its upper end, made in the direction of the line of motion of the machine, in combination with the brace-rod U, pivoted at its lower end and provided at its upper end with a slot registering with that in the arch S, adjustable 125 rake-support B, and bolt T, substantially as described, and for the purpose set forth.

JOHN HARRIS.

In presence of—

WILLIAM COX,

ALBERT WESTOVER.
